DESIGN FOR A DRESS ENSEMBLE

Marie Mascitelli, New York, N. Y.

Application October 8, 1938, Serial No. 80,320

Term of patent 3½ years

To all whom it may concern:

Be it known that I, Marie Mascitelli, a citizen of the United States of America, residing in New York city, in the Borough of Manhattan, county and State of New York, have invented a new, original, and ornamental Design for a Dress Ensemble, of which the following is a specification, reference being had to the accompanying drawing, forming part thereof, wherein—

I claim:

The ornamental design for a dress ensemble, substantially as shown.

MARIE MASCITELLI.
